DESIGN FOR A HAND MIRROR

Edward Marder, Brooklyn, N. Y.

Application March 18, 1936, Serial No. 61,687

Term of patent 3½ years

To all whom it may concern:

Be it known that I, Edward Marder, a citizen of the United States, residing at Brooklyn in the county of Kings and State of New York, have invented a new, original, and ornamental Design for Hand Mirrors, of which the following is a specification, reference being had to the accompanying drawing, forming part thereof.

The figure is a plan view of a hand mirror, showing my new design. The hand mirror is of conventional thickness.

The dominant feature of my design is the surface ornamentation appearing on the mirror back.

I claim:

The ornamental design for a hand mirror, substantially as shown and described.

In testimony whereof I have hereunto subscribed my name.

EDWARD MARDER.
